ANIMATED TOY

Christopher Luckhaupt, Jamaica, N. Y.

Application April 6, 1946, Serial No. 660,217

1 Claim. (Cl. 46—119)

1

My present invention relates to animated toys. More particularly, the invention is directed to toys comprising objects simulating humans and/or other animals, being selected as typical. Such animated object is mounted on a hollow base, the legs, and neck, or other elements of such animated object being articulated, as by forming such articulated elements individually of hollow parts arranged in serial relation and strings of limited stretchability passing through such articulated hollow parts, and respective strings at their one ends being fixed, the other ends of such strings being secured to a block of wood or like rigid element disposed laterally within an open-bottomed hollow base, a resilient element, preferably sponge rubber, being interposed within the hollow base between its closed top and the upper face of such block, the block being held in displaceable relation to the sides and to the top of the hollow base by a sheet of resilient material secured at its edge portions to the hollow base at mutually spaced locations, whereby upon exerting pressure upon such resilient material at variant locations and with variant degree, such object is subjected to animation, in variant natural or unnatural action.

Further features and objects of the invention will be more fully understood from the following detailed description and the accompanying drawings, in which:

Fig. 1 is a front elevational view of an animated toy constructed pursuant to the invention, showing a giraffe as the animated object, this view illustrates such object in a normal pose.

Fig. 2 is a side elevation of Fig. 1.

Fig. 3 is a central vertical sectional view, somewhat diagrammatic, of Figs. 1 and 2.

Fig. 4 is a perspective view of Figs. 1 and 2, showing the object in an animated pose.

Fig. 5 is a detail sectional view on line 5—5 of Fig. 1.

Fig. 6 is a detail sectional view on line 6—6 of Fig. 2.

Fig. 7 is a detail bottom perspective view of the hollow base assembly of the toy shown in Figs. 1, 2, 3 and 4.

Fig. 8 is a detail side perspective view, indicating one manner of fixedly tying the upper ends of the strings, namely at the upper terminus of the neck element, the head of the object being secured in position by means of a socket making a frictional fit over the upper terminus of the neck, thus serving to conceal the tied fixed ends of the strings.

Fig. 9 is a front elevational view of another

2

embodiment of my toy, illustrating two objects typified by a female figure and a male figure which may be individually animated pursuant to the invention.

5 Fig. 10 is a diagrammatic vertical sectional view of the male figure of Fig. 9.

Fig. 11 is a plan view of one form of base applicable to the embodiment of Fig. 9.

10 Fig. 12 is a plan view of another form of base applicable to the embodiment of Fig. 9.

Referring to Figs. 1 through 8, 10 designates generally an object preferably simulating a live object typified by a giraffe. 11 designates the hollow base, shown as rectangular in configuration, which is closed at its top 11a and substantially open at its bottom 11b.

15 Such simulated object 10, as shown, comprises a body portion 12, which as appears from Fig. 3 is provided at appropriately spaced locations in its lower portions with perforations 13 appropriate for articulated connection with the legs 14. Such perforations 13 communicate with the enlarged recess 15 which is disposed centrally of the body 12 and which extends from the zone of attachment of the tail 16 and ends at a location toward the front of the body. At the frontal portion of such recess 15 lead the perforations 17 which end at the lower end of the articulated neck 18.

20 Since the illustrated object has four legs, the perforations 13 are four in number and correspondingly the number of perforations 17 may be the same.

25 As shown, the legs 14 and the neck 18 are articulated by the provision of individual longitudinally extending centrally perforated elements. In the instance of the illustrated giraffe figure, the lowermost perforated element 14a of each leg is of hoof formation, the lower face of which engages the upper face 11a of the hollow base, the remaining elements of each leg being of general elongated formation, their mutually engaging faces being preferably of ball and socket formations, to facilitate mutually relative displacement of the respective elements of each leg, in similitude to natural articulation or movement in weird manner, as may be selectively desired, as appears more fully hereinafter.

30 The articulated neck 18 is shown comprising four articulatable elements each having four longitudinally extending perforations. The number of perforations in each articulated element of the neck may be from one to four, as preferred.

35 Strings, in this instance four in number, see Fig. 3, extend through the perforations of the neck elements 18, the upper ends of such strings

being fixed relative to the upper terminus 18a of the neck 18. Such fixing of the upper ends of the strings may be had by tying the two strings to one another and the other two strings to one another. These strings continue from the neck elements through the respective perforations 17, 17 of the body 12, then through the perforations 13, 13, and thence through the perforations of the elements of the respective legs 14. The strings that pass through the perforations of the articulated elements of the front legs are designated 19. The remaining two strings, designated 20, extend through the perforations, designated 17a, of the upper portion of the body 12, then through the recess 15 and thence through the perforations of the elements of the hind legs 14a.

The lower ends of the strings 19, 19, 20, 20, as also appears from Fig. 3, extend through suitable perforations in the top of the base and are secured to the block 21, as at its upper face. Such block may be of wood. In the instance where the hollow base 11 is rectangular, as shown, the block 21 is of corresponding configuration but of lesser dimensions whereby the block is freely displaceable relative to the lateral walls of the base 11. Interposed between the upper face of the block 21 and the inner face of the top 11a of the base is a mass 22 of soft rubber, such as sponge rubber, shown as a block member of rectangular configuration which is dimensioned so as to substantially fill the upper portion of the hollow base, said block member having vertical perforations 22a aligned with the perforations in the base top for passage therethrough of the respective strings 19, 19, 20, 20, such arrangement preventing undue wear on the strings.

The block 21 is disposed within the hollow base 11 to afford displacement in variant direction and extent as by securement at its lower face to a flexible member, such as a sheet 23 of flexible rubber, shown in Fig. 7, of polygonal configuration, in this instance of quadrilateral formation, its four apices 23a being individually secured to the bottom of the base as by means of tacks 24, or the like; the securement of the flexible rubber 23 to the block 21 is shown by means of a nail 25, passing centrally through the rubber sheet 23.

The parts of the toy are assembled in the following manner. The strings 19, 19, 20, 20 are first secured at their lower ends to the block 21 at mutually spaced locations, then respectively threaded through the perforations 22a of the rubber member 22, then through the respective leg elements of the object, thence through the recess 15 of the body 12 of the object, the tail 16 being removed to afford such manipulation; the further manipulation of the strings 19, 19, is through the recess 17, 17, and the strings 20, 20 through the perforations 17a, 17a of the body, and finally through the perforations of the elements of the neck member 18, the length of each string being ample to extend beyond the upper terminus 18a of the neck 18. The yieldable member 23, attached to the block 21, is then secured to the bottom face of the base 11. The strings are then drawn taut to a proper extent to effect partial compression of the rubber member 22, i. e. by the block 21 and also to tension inwardly the resilient member 23. The upper ends of the strings are then tied, as above indicated and as illustrated in Fig. 8. The head 26 is placed in fixed relation with the upper terminus 18a of the neck as by frictional engagement therewith and may be placed in position simulating a natural pose, or as desired in an unnatural position, dependent

upon the vagaries of the user. The tail 16 is shown as a single element, the inner end being tapered to form a friction fit with the exterior opening of the recess 15. If desired, the tail may be formed of articulated elements, similarly perforated as illustrated with respect to the articulated elements of the legs and the neck through which perforations a string passes, one end of which is secured to the block 21 and the other end to the terminus of the tail.

Upon assembly of the respective parts of the simulating object, its antics are effected by the user by variantly compressing the compressible element 23 in degree and location or locations, causing relative less tautness of the respective strings passing through the articulated parts. Fig. 4 illustrates an animated position of the illustrated giraffe, it being understood that any number of natural and unnatural movements of the respective parts of the object are available by selectively varying the location or locations and degree of pressure applied to the rubber member 23. In such operation the sponge rubber, or equivalent resilient material 22, undergoes varying extent of compression of the respective portions of its mass, effecting variant degrees of partial release of tautness of the respective strings, enhancing the prantics of the animated figure. Such enhanced action is attained by coordination of the solid block 21 and by the flexible member 23 with the sponge rubber member 22, the rubber member 23, upon release of pressure exerted by the user, serving also to return the block 21 to or toward its normal position, this imparting variant release of pressure upon variant portions of the sponge rubber member 22.

It will be observed that the provision of securement of the block 21 to the flexible member 23 affords positioning the block 21 normally wholly within the hollow base 11, thus enabling the toy when non-operated to be stably placed upon a table or like support.

In like manner, two or more simulated objects may be embodied in the toy. Thus, as illustrated in Figs. 9 and 10, an object 30 simulating a woman and an object 31 simulating a man may serve as the animated objects, and as shown may be positioned to face one another, to simulate folk dancing, etc. The articulated elements of the woman, as shown, comprise the legs and arms, viz. each two in number, and similarly with respect to the articulated elements of the man. In such arrangement, as diagrammatically illustrated in Fig. 10, with respect to the male figure 31, two strings pass through perforations of one leg, thence through the vertical recess 34 in the body 31a of the figure, the end of one string 32 being fixedly secured at the upper terminus of the neck 31b, the other string 32a continuing at the upper end of the recess 34 through the perforations of the articulated elements of one arm, its one end being fixed therat. The opposite ends of the strings 32, 32a are secured to the block 21, which is coordinated with the sponge rubber member 22 and the block 21 yieldably held under tension by an individual flexible member 23, similarly as described hereinabove with reference to the embodiment of Figs. 1 through 7. Similar assembly is carried out with respect to the strings 33, 33a, respectively having one end fixedly secured to the terminus of the neck of the male figure and at the terminus of the other arm, the opposite ends of such strings 33, 33a, being fixed to the block 21, similarly as above. Fig. 11 illustrates such individual assembly of these parts for the respec-

tive figures 30, 31, in which instance the hollow base 11 may have an oval configuration.

Fig. 12 illustrates, on somewhat reduced scale, a hollow base 40, shown of oval configuration, in which is enclosed a single sponge rubber member 41, also of oval configuration of lesser dimensions than the oval interior of the base 40, a block of wood 42, also of oval configuration of corresponding dimensions as the block 42, and a single flexible member 43, of polygonal configuration, secured at its center by a nail 44 to the center of the block 42, and at its apices 43a to the bottom rim of the hollow base 41.

I claim:

A toy comprising a figure having a plurality of articulated engaging elements provided with communicating perforations; a hollow base supporting said figure on its top, said base having perforations in its top communicating with the element perforations and having an open bottom; a block of non-yielding material having lesser horizontal dimension than the interior of the base whereby it is displaceable and tiltable therein; a member of flexible material secured at its periphery adjacent the open bottom of said base; means for attaching said flexible member centrally to said block of non-yielding material; an elastic member of sponge rubber interposed

5 between said block and the inner face of the top of said base; said member having vertical perforations aligned with the perforations of the top of the base and having horizontal dimensions such that it substantially fills the base; and string means having one end thereof secured to said block and extending through the perforations of said sponge rubber member and of the top of said base and thence through the perforations of the articulated elements and having its other end fixedly secured to an upper portion of said figure, said sponge rubber member normally tensioning said string means, and said block being operative to vary the tension of said string means.
